TUNNELING MACHINE WITH TANDEM SPOIL BARRIERS

John R. Tabor, Racine, Wis., assignor to Mining Equipment Manufacturing Corporation, Racine, Wis.
Original application July 9, 1968, Ser. No. 743,363, now Patent No. 3,561,223, dated Feb. 9, 1971. Divided and this application Feb. 24, 1970, Ser. No. 16,993
Int. Cl. E01q 3/03

U.S. Cl. 299—33

7 Claims

ABSTRACT OF THE DISCLOSURE

A tunneling machine for excavating through relatively muck earth strata generating fluid spoil, said machine having a shield with a fixed substantially closed bulkhead and an excavating wheel ahead of the bulkhead, said wheel having a face which can be substantially completely closed to breast fluid spoil, whereby two spoil barriers in tandem resist flow of fluid spoil. The wheel has a substantially closed front face with radially elongated openings, transversely extending pintles spanning said openings at a point intermediate the radial extent thereof and gates swingable on said pintles to selectively open and close said openings, gate portions at one side of the pintle moving outwardly beyond the front wall as gate portions at the other side of the pintle move inwardly of said wall.

CROSS REFERENCE TO RELATED APPLICATION

This application is a division of copending U.S. patent application Ser. No. 743,363, filed July 9, 1968, now U.S. Pat. 3,561,223 granted Feb. 9, 1971, the entire disclosure of which is incorporated herein by reference.

SUMMARY OF THE INVENTION

The invention is summarized in the foregoing abstract.

DESCRIPTION OF THE DRAWINGS

FIGS. 1-22, inclusive, are illustrated and described in said copending patent.

DESCRIPTION OF THE PREFERRED EMBODIMENT

Although the disclosure hereof is detailed and exact to enable those skilled in the art to practice the invention, the physical embodiments herein disclosed merely exemplify the invention which may be embodied

2

in other specific structure. The scope of the invention is defined in the claims appended hereto.

The entire disclosure of said copending U.S. Pat. 3,561,223 is incorporated herein by reference. Particular attention is invited to FIGS. 1, 3, 4, 5 and 6 thereof and to the description relating thereto.

What is claimed is:

1. An excavating wheel for a tunneling machine, said wheel having a substantially closed front face with radially elongated openings, transversely extending pintles spanning said openings at a point intermediate the radial extent thereof and gates swingable on said pintles to selectively open and close said openings, gate portions at one side of the pintle moving outwardly beyond the front wall as gate portions at the other side of the pintle move inwardly of said wall.

2. The device of claim 1 in combination with power means to swing said gates on said pintles.

3. The device of claim 2 in which said power means comprises a fluid motor having its thrust axis transverse to the tunnel axis, a link extending axially of the tunnel and connected to the inner ends of the gates, and a right angle motion transmitting connection between the power means and the link.

4. A tunneling machine for excavating through relatively mucky earth strata generating fluid spoil, said machine having a shield with a fixed substantially closed bulkhead and an excavating wheel ahead of the bulkhead, said wheel having a face which can be substantially completely closed to breast fluid spoil, whereby two spoil barriers in tandem resist flow of fluid spoil.

5. The machine of claim 4 in which there is a seal circumferentially about said shield and overlapping the edge of the wheel to close the gap between the shield and the wheel.

6. The machine of claim 4 in which said wheel face has openings and gates in said openings, and power means for moving said gates into and out of said openings.

7. The machine of claim 4 in which said bulkhead has a spoil removal opening, a tube through said opening, a seal between said tube and bulkhead, and means for pumping fluid spoil from said tube.

UNITED STATES PATENT OFFICE
CERTIFICATE OF CORRECTION

Patent No. 3,667,808 Dated June 6, 1972

Inventor(s) John R. Tabor

It is certified that error appears in the above-identified patent and that said Letters Patent are hereby corrected as shown below:

Column 1, Line 15, change "muck" to - mucky -

Column 1, Line 25, delete "mucky earth strata generating fluid spoil, said machine" and insert ---
---open and close said openings, gate
portions at one ---

Signed and sealed this 31st day of October 1972.

(SEAL)
